(57) **CLAIM**

The ornamental design for a gaming machine, as shown and described.

DESCRIPTION

FIG. 1 is a perspective view of a gaming machine in accordance with the invention.

FIG. 2 is front view of the gaming machine shown in FIG. 1.

FIG. 3 is side view of the gaming machine shown in FIG. 1, the left and right side views being mirror images of one another.

FIG. 4 is a rear view of the gaming machine shown in FIG. 1; and,

FIG. 5 is a top view of the gaming machine shown in FIG. 1.

Views of the bottom of the gaming machine are omitted because the bottom is flat and devoid of surface ornamentation.

The broken lines indicate unclaimed portions of the article and form no part of the claimed design.
